FLATIRON CONSTRUCTION

Filed July 8, 1925

FIG. 2.

FIG. 4.

FIG. 3.

Inventor

MARTIN C. BERSTED

By A. B. Bowman

Attorney

UNITED STATES PATENT OFFICE

MARTIN C. BERSTED, OF SAN DIEGO, CALIFORNIA

FLATIRON CONSTRUCTION

Application filed July 8, 1925. Serial No. 42,190.

My invention relates to flat iron construction, more particularly to means of connecting the handle to the body of the iron, and the objects of my invention are: First, to provide a simple, economical and efficient means of securing a handle to the upper portion of the body of a flat iron; second, to provide a construction for a flat iron in which the handle supporting members or straps are rigidly secured to the body of the flat iron by means of a single screw; third, to provide a flat iron in which the handle supporting means is made of two straps interlocked with each other, the securing screw and the casing of the iron at their one ends, so that a simple and rigid connection is made, one which permits the iron to be readily assembled or disassembled; fourth, to provide a handle supporting strap means which may be punched from one piece into two pieces without waste of material; fifth, to provide novelly constructed handle supporting members or straps whereby the heat normally conducted from the body of the iron to the handle is reduced to a minimum; sixth, to provide a novelly constructed flat iron, and seventh, to provide an iron of this class which is durable and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a side elevational view of my electric flat iron, showing certain parts and portions thereof broken away and in section to facilitate the illustration of the means of securing the handle to the body of the flat iron; Fig. 2 is a fragmentary sectional view thereof, taken through 2-2 of Fig. 1; Fig. 3 is a fragmentary sectional elevational view thereof, taken through 3-3 of Fig. 1, showing certain parts and portions in elevation to facilitate the illustration, and Fig. 4 is

a fragmentary front end view thereof, taken at 4-4 of Fig. 1.

Like characters of reference refer to similar parts and portions throughout the several views of the drawings.

The casing 1, for enclosing the upper plate and the operating and switch mechanism thereof, is mounted on the base plate 2 as in the conventional construction. The upper portion of the casing 1 at its median line is upwardly offset forming a longitudinal channel 1^a at its inner side, as shown best in Fig. 3. Near the front end and at the rear end of the upper wall forming this channel portion 1^a are provided transverse slots 1^b and 1^c through which extend, respectively, the handle supporting members or straps 4 and 5. These straps 4 and 5 are of substantially the same width as the channel portion 1^a and are positioned with their inner ends therein. Said straps are punched from one piece, being severed in such a manner as to provide a stepped or Z-shaped joint in a common plane as illustrated in Fig. 2. Intermediate the ends of the adjacently positioned longitudinally extending edges 4^a and 5^a at the abutting ends of the straps 4 and 5 are provided oppositely positioned, semicircular recesses 4^b and 5^b, forming a circular hole for the reception of the shank of the screw 6, which extends downwardly through a hole in the casing and is secured at its lower end into the upper plate 3 of the iron, as shown in Figs. 1 and 3. In the iron shown in the drawings there is provided a bridge member 7 for supporting the switch and other mechanism within the casing of the iron. This bridge member extends longitudinally within the casing and is positioned on the upper plate 3, as shown in Figs. 1 and 3. The ends 4^c and 5^c of the supporting members 4 and 5 extending within the casing are clamped against the bridge member 7 by the screw 6 and are forced with said inner ends into the channel 1^a of the casing, thus providing a rigid, simple and economical construction for securing the members 4 and 5 to the body of the flat iron.

The handle supporting members or straps 4 and 5 extend upwardly from the body of the

flat iron and are cupped at their upper ends, as indicated by 4^a and 5^a, which provides only a small engaging edge of said straps against the ends of the handle 8 positioned 5 therebetween and secured thereto by means of a long screw 9 and nut 9^a extending axially through the handle. The straps 4 and 5 are longitudinally perforated near their upper ends secured to the handle 8, as shown 10 best in Fig. 4, thus cutting down the cross-sectional area materially and reducing the conduction of heat to the handle to a minimum, the construction of the upper ends of said straps also reducing the conduction of 15 heat from said straps to the handle to a minimum.

Though I have shown and described a particular construction, combination and arrangement of parts and portions, I do not 20 wish to be limited to this particular construction, combination and arrangement, but desire to include in the scope of my invention the construction, combination and arrangement substantially as set forth in the appended 25 ed claims.

Having thus described my invention, what I claim as new and desire to secure by Letters Patent is:

1. In a flat iron structure, including a hot 30 plate, a casing provided at its upper portion with an inverted, upwardly extending channel portion, a handle, a pair of handle supporting straps of substantially the width of said channel, the one end portions of said 35 straps being connected to opposite ends of said handle, the other end portions of said straps extending into said casing and lengthwise within said channel with their ends in abutment therein, the lower surface of said 40 end portions lying substantially flush with the inner surface of said casing and in equal spaced relation with the upper surface of said hot plate, and unitary means for securing said members in and to said casing.

2. In a flat iron structure, a casing provided with a pair of openings in its upper portion, an upper plate positioned within said casing, a bridge member between said upper plate and said casing, a handle, a pair of handle supporting members each having one 50 end attached to said handle and the other end extending through one of said openings and abutting against each other at said ends between said bridge member and said casing, 55 said abutting ends forming a stepped joint in a common plane, and a screw extending through said casing and said bridge member and through recesses at the adjacent edges of the abutting ends of said members clamping the inner ends of said members between the casing and said bridge member.

3. In a flat iron structure, a casing provided at the inner side of its upper portion with a medially extending inverted channel portion 60 having transverse slots near its forward

and rear ends, a handle, a pair of handle supporting straps each having one end attached to said handle and the other end extending through one of said slots and positioned with said ends in said channel portion, the inner ends of said straps being offset laterally and abutted at said offset ends with each other with the sides forming said offset ends being positioned adjacent each other, an upper plate positioned within said casing, 70 a bridge member positioned within said casing on said upper plate, and a single screw extending through said casing and through recesses in the adjacent sides of the abutting ends of said straps, positively locking the inner ends of said straps relatively to each other in said channel portion and securing the inner ends thereof against the upper side of said bridge member and said bridge member against said upper plate.

4. In a flat iron structure, a casing provided at the inner side of its upper portion with a medially extending inverted channel portion having transverse slots near its forward and rear ends, a handle and a pair of handle supporting straps each having one end attached to said handle and the other end extending through one of said slots and positioned with said ends in said channel portion, the inner ends of said straps being offset laterally and abutting each other with the sides forming said offset ends being positioned adjacent each other, and means removably securing the abutting ends relatively to each other and to said casing.

5. In a flat iron structure, the combination with the outer casing of said iron, of a pair of handle supporting straps removably secured to said casing, a handle member supported between the outer ends of said straps, 105 said outer ends having relatively large, cup shaped, inwardly facing depressions therein and forming relatively narrow lines of contact with said handle member.

In testimony whereof, I have hereunto set my hand at San Diego, California, this 29th day of June, 1925.

MARTIN C. BERSTED.
